US00D571843S

(12) **United States Design Patent**
Lee et al.

(10) **Patent No.:** US D571,843 S
(45) **Date of Patent:** ** Jun. 24, 2008

(54) **DIGITAL CAMERA**

(75) Inventors: **Eun-kyung Lee**, Seoul (KR);
Seung-seup Yoo, Seoul (KR); **Sung-hwa Chang**, Seoul (KR)

(73) Assignee: **Samsung Techwin Co., Ltd.**, Changwon (KR)

(**) Term: **14 Years**

(21) Appl. No.: **29/285,660**

(22) Filed: **Apr. 5, 2007**

(30) **Foreign Application Priority Data**

Oct. 17, 2006 (KR) 30-2006-0041700

(51) **LOC (8) Cl.** 16-01

(52) **U.S. Cl.** D16/202

(57) **CLAIM**

The ornamental design for a digital camera, as shown and described.

DESCRIPTION

FIG. 1 is a perspective view of a digital camera;
FIG. 2 is a front elevational view of the digital camera;
FIG. 3 is a rear elevational view of the digital camera;
FIG. 4 is a left side elevational view of the digital camera;
FIG. 5 is a right side elevational view of the digital camera;
FIG. 6 is a top plan view of the digital camera;
FIG. 7 is a bottom plan view of the digital camera;
FIG. 8 is a rear perspective view of the digital camera;
FIG. 9 is a front perspective view of the digital camera, where the display unit is rotated by 90°;
FIG. 10 is a rear perspective view of the digital camera, where the display unit is rotated by 90° and buttons are exposed; and,
FIG. 11 is a rear perspective view of the digital camera, where the display unit is rotated by 180° and buttons are exposed.
The broken lines in Figures are for illustrative purposes only and form no part of the claimed design.
